AQUA SLED

Tak Kimura, 1021 W. 42nd Place, Los Angeles, Calif.

Filed Mar. 9, 1961, Ser. No. 64,206

Term of patent 14 years

(Cl. D71—1)

FIGURE 3 is a side elevational view thereof, the opposite side being substantially the same in appearance;

What is claimed is:

The ornamental design for an aqua sled, substantially as shown and described.
